UNITED STATES PATENT OFFICE

128,655

DESIGN FOR AN OVERHEAD PILOTED VERTICAL SLIDE TOOL FOR LATHES OR THE LIKE

Oskar Kylin, Cleveland, Ohio

Application June 3, 1941, Serial No. 101,271

Term of patent 7 years

To all whom it may concern:

Be it known that I, Oskar Kylin, a citizen of the United States, residing at Cleveland, in the county of Cuyahoga and State of Ohio, have invented a new, original, and ornamental Design for Overhead Piloted Vertical Slide Tools for Lathes or the like, of which the following is a specification, reference being had to the accompanying drawing, forming part thereof.

In the drawing:

Figure 1 is a front elevational view of an overhead piloted vertical slide tool for lathes or the like showing my new design;

Figure 2 is a side elevational view of the tool shown in Figure 1 and looking at the right hand side; and

Figure 3 is a top plan view of the tool looking down on Figure 1.

I claim:

The ornamental design for an overhead piloted vertical slide tool for lathes or the like, as shown.

OSKAR KYLIN.
